COMBINED CRUTCH, ASH TRAY, GLASS
HOLDER AND HORN THEREFOR

Connie E. Blum, 6233 N. 68th St. 68104, and Donald E. Hyde, 2705 Margo St. 68147, both of Omaha, Nebr.

Filed Feb. 5, 1970, Ser. No. 21,280

Term of patent 14 years

Int. Cl. D3—03
U.S. Cl. D88—4

FIG. 5

FIG. 3

FIG. 1

FIG. 4

FIG. 2

FIG. 6

FIG. 1 is a front elevational view of a combined crutch, ash tray, glass holder and horn therefor showing our new design;

FIG. 2 is a rear elevational view thereof;

FIG. 3 is a left side elevational view thereof;

FIG. 4 is a right side elevational view thereof;

FIG. 5 is a top plan view thereof; and

FIG. 6 is a bottom plan view thereof.

We claim:

The ornamental design for a combined crutch, ash tray, glass holder and horn therefor, substantially as shown.
